L. G. CHAMBERLAIN

WRENCH

Filed June 9, 1924

Inventor
Louis G. Chamberlain

By Herbert E. Smith
Attorney

UNITED STATES PATENT OFFICE.

LOUIS G. CHAMBERLAIN, OF SETTERS, IDAHO.

WRENCH.

Application filed June 9, 1924. Serial No. 718,744.

To all whom it may concern:

Be it known that I, LOUIS G. CHAMBERLAIN, a citizen of the United States, residing at Setters, in Kootenai County and State of Idaho, have invented certain new and useful Improvements in Wrenches, of which the following is a specification.

My present invention relates to improvements in wrenches of the type known as alligator wrenches, utilizing a pair of jaws pivoted on a single pin in a handle used as a lever grip.

The primary object of the invention is the provision of a hand tool or implement of this character which may be used either in straight alined position of the jaws and handle, or with the jaws disposed at an angle to the handle or lever grip, thus readily adapting the tool for many different uses.

The invention consists in certain novel combinations and arrangements of parts which permit of both the angular and straight adaptation of the tool for use, in adjusting the jaws for use on various sizes of objects, and in details of construction as will be hereinafter set forth and claimed.

In the accompanying drawings I have illustrated one complete example of the physical embodiment of my invention wherein the parts are combined and arranged in accordance with the best mode I have thus far devised for the practical application of the principles of my invention.

Figure 1 is a perspective view of an implement embodying my invention the jaws being alined with the handle for use as a straight wrench.

Figure 2 is an enlarged detail view at the working end of the tool showing the jaws disposed angularly with relation to the handle, and showing also by dotted and full lines the range of adjustment of the jaws, part of the handle being broken away for convenience of illustration.

Figure 3 is a detail view of a fragment of the tool showing the adjustable relation of one of the operating links.

The lever handle 1 used for the purpose of gripping the tool is of convenient size and shape for manipulation and is formed with an end socket 2 which is fashioned with an abrupt shoulder 3 that extends perpendicular to the longitudinal axis of the handle. Two complementary toothed jaws 4 and 5 are pivoted in the handle-socket on

the single pivot pin 6 which extends transversely through the handle and is secured therein. One of the jaws as 4 is fashioned with a notch 7 in its edge adjacent to the shoulder 3 and these two members, the shoulder and notch are adapted to engage when the implement is to be used as a straight wrench, as in Figure 1. The engagement of the notch with the shoulder affords a rigid and braced connection between the handle and the jaw 4, the latter forming an alined extension of the handle. The jaw is permitted to swing to one side of the longitudinal center of the lever handle but is prevented by the notch and shoulder engagement from swinging to the other side of the longitudinal center of the handle.

On both sides of the wrench is arranged a linkage connection between the handle and the jaws, each connection comprising a Y-shaped arrangement of levers or links as 8, 9 and 10. The links 8 at opposite sides of the tool are connected by a fulcrum pin 11 which is provided with heads 12. The pin passes through a slot 13 in the handle, which is of curved formation and disposed slightly at an angle to the longitudinal axis of the handle. At the side of the tool toward which the jaws may swing when angularly adjusting them, the wall of the slot 13 is notched as at 14 and adapted to receive the pin 11.

The three links at each side of the tool are pivoted together on a single pin 15 and the two outer ends of the links 9 and 10 are pivoted at 16 and 17 respectively to the jaws 4 and 5.

To increase the leverage of the operating links a pinhole 18 is provided at the ends of the links 8 on opposite sides of the wrench, and the fulcrum pin 11 may be used to connect the two links 8 at these perforated ends. This arrangement of the pin 11 with relation to the perforated ends of the links permits of a wider extension or opening of the jaws that is secured in the arrangement shown.

When the tool is used as a straight wrench jaw 4 is moved to alined position with the lever handle 1 as in Figure 1 with the notch 7 engaging the shoulder 3, and pin 11 is located in the offset slot or notch 14 of the handle.

To swing the jaws to angular position with relation to the handle, pin 11 is first moved into the main slot 13 away from pin

6 for the purpose of bodily swinging the jaws to the desired angular position. Then the jaws may be opened or separated by pushing pin 11, which is guided in its slot 5 13, toward the pin 6. This action tends to bring the links 9 and 10 into alinement, and relatively extends the jaws 4 and 5 for use.

The nearer pin 11 is brought toward pin 6 the wider are the jaws opened within limits of the slot 13. When manipulating the wrench, the heads 12 at the two ends of the fulcrum pin 11 are grasped by the thumb and finger in order that the relative positions of the jaws may be maintained. The 15 handle 1 is used as a lever arm for turning the object grasped by the jaws of the tool.

Having thus fully described my invention what I claim as new and desire to secure by Letters Patent is—

20 1. The combination with a slotted lever handle having a socket and a shoulder, of a

pair of jaws having a single pivot in the socket and a notch on one of the jaws for engagement with said shoulder, a Y-shaped linkage comprising a link and a pin in the 25 slotted handle, a pair of links pivoted to the respective jaws, a single pivot pin connecting the three levers, and a notch in the slotted lever handle.

2. The combination with a lever handle 30 having a slot, of a pair of pivoted jaws having a single pivot pin in the handle, a fulcrum pin extending through the slot in the handle and provided with exterior heads, 35 links at opposite sides of the handle connected to said pin, and a pair of links at each side of the handle pivoted to the first mentioned links and pivoted to the respective jaws.

In testimony whereof I affix my signature.

LOUIS G. CHAMBERLAIN.
